207,096

COMBINATION BATHTUB AND SHOWER STALL

James A. Osika, Urbana, Ill., assignor to Whirlpool
Corporation, a corporation of Delaware

Filed Apr. 11, 1966, Ser. No. 1,830

Term of patent 14 years

(Cl. D4—4)

FIGURE 1 is a front elevation of a combination bathtub and shower stall embodying my new design;

FIGURE 2 is a top plan view thereof;

FIGURE 3 is a fragmentary vertical section taken substantially along the line 3—3 of FIGURE 1;

FIGURE 4 is a fragmentary vertical section taken substantially along the line 4—4 of FIGURE 2;

FIGURE 5 is a vertical section taken substantially along the line 5—5 of FIGURE 2; and

FIGURE 6 is a fragmentary vertical section taken substantially along the line 6—6 of FIGURE 5.

I claim:

The ornamental design for a combination bathtub and shower stall, as shown.

UNITED STATES PATENT OFFICE
Certificate

Patent No. D. 207,096

Patented March 7, 1967

James A. Osika

Application having been made by James A. Osika, the inventor named in the patent above identified, and Whirlpool Corporation, a corporation of Delaware, the assignee, for the issuance of a certificate under the provisions of Title 35, Section 256, of the United States Code, adding the name of Merritt W. Seymour as a joint inventor, and a showing and proof of facts satisfying the requirements of the said section having been submitted, it is this 27th day of April 1971, certified that the name of the said Merritt W. Seymour is hereby added to the said patent as a joint inventor with the said James A. Osika.

FRED W. SHERLING
Associate Solicitor.

UNITED STATES PATENT OFFICE
CERTIFICATE OF CORRECTION

Patent No. Design No. 207,096 Dated March 7, 1967

Inventor(s) James A. Osika et al.

It is certified that error appears in the above-identified patent and that said Letters Patent are hereby corrected as shown below:

In the grant, lines 1 and 2, "assignor to Whirlpool Corporation, a corporation of Delaware," should read -- said Osika assignor to Whirlpool Corporation, a corporation of Delaware and said Seymour assignor to Owens-Corning Fiberglas Corporation, a corporation of Delaware --; line 9, "is" should read -- are --; line 12, "Whirlpool Corporation, its successors" should read -- Whirlpool Corporation and Owens-Corning Fiberglas Corporation, their successors --. In the heading to the drawing and printed specification, lines 3 and 4, "assignor to Whirlpool Corporation, a corporation of Delaware" should read -- said Osika assignor to Whirlpool Corporation, a corporation of Delaware and said Seymour assignor to Owens-Corning Fiberglas Corporation, a corporation of Delaware --.

Signed and sealed this 10th day of August 1971.

(SEAL)
